2,594,974

SELF-CLEARING STAR FEEDER

Lauritz Emil Mylting, Philadelphia, Pa., assignor
to The Allen-Sherman-Hoff Company, Phila-
delphia, Pa., a corporation of Pennsylvania

Application February 17, 1948, Serial No. 8,840

6 Claims. (Cl. 241—36)

1

The present invention relates generally to the art of handling and conveying solids, and is more particularly concerned with a novel method for feeding solids and automatically breaking up pieces of material therein which are larger than a predetermined maximum size, and with a novel device implementing that method.

Removal of ashes from hoppers of solid fuel burning furnaces such as industrial steam boilers has been complicated by the presence of clinkers which exceed the maximum size which can be handled by the handling apparatus provided therefor. It is important in such operations to remove the ash expeditiously and without interruption by clinkers or other bodies too large to be handled by the handling means. Such removal should not admit gases into the hopper because the admission of gases decreases the efficiency of the furnace operation. Open or movable gratings which screen out clinkers which exceed the maximum permissible size are unsatisfactory because it is necessary to open the housing to permit a workman to break up such clinkers, and at such times air may flow in large volumes into the combustion chamber.

Feeders of the rotary valve type are not satisfactory, for when an oversize clinker enters the rotor, the keys connecting it to the drive shaft are sheared off, thus stopping the ash removing operation until the clinker is removed and the drive keys are replaced.

In accordance with the present invention, not only can satisfactory air or gas sealing be effected, but also oversize clinkers in the ash may be rapidly and automatically broken up without materially affecting the normal ash removal operation. Disintegration of clinkers is performed by this invention in a novel manner by subjecting the clinker to rapidly repeated impacts. The clinker is subjected to hammer-like blows delivered alternately to opposite sides thereof while it is supported as by an anvil. This rapid, reverse hammering quickly breaks the clinkers to sizes which can be handled with no more than slight delay in the rate of ash removal, and does not result in breakage of the feeder or admission of air to the hopper.

Briefly stated, the method of my present invention thus comprises the steps of removing ashes and clinkers from a combustion chamber, subjecting each oversize clinker to repeated impacts delivered alternately on opposite sides of the clinker and thereby reducing such clinker to pieces smaller than a predetermined maximum size, and moving the ashes and reduced clinkers

2

to a place where they may be stored or further treated. In using this method with a modern boiler installation, the operations are preferably continuous, the ashes and clinkers falling into a hopper below the chamber as rapidly as they are produced, and substantially continuously moving the reduced clinkers and ashes to a zone at atmospheric pressure through a gas lock so that combustion is not disturbed when the combustion chamber is under a gas pressure different than atmospheric pressure.

Although the present invention is important in solving the long standing ash handling problem, it is not limited in its use thereto, for it may be used in handling solids composed of any material where the pieces are of different sizes and some are larger than the handling capacity of the handling apparatus.

One embodiment of this invention is a rotary feeder having a fixed shoe disposed close to the rotor and means for repeatedly reversing the rotor and thereby striking blows on opposite sides of a solid which is in the rotor and is too large to be moved past the shoe.

25 In the drawings accompanying and forming a part of this specification:

Fig. 1 is a perspective view partly broken away showing one embodiment of the present invention;

30 Fig. 2 is a horizontal sectional view taken on line 2—2 of Fig. 1;

Fig. 3 is a fragmentary vertical sectional view taken on line 3—3 of Fig. 2; and

35 Fig. 4 is a wiring diagram showing the motor and motor-reversing connections.

The device illustrated in the accompanying drawings is a feeder which is specifically adapted for removing ash from hoppers of solid fuel burning furnaces. The illustrated device comprises a housing 1 provided with a flange 2 at the upper side for attachment to a hopper. The housing has an opening 3 at its upper end within flange 2 and through which solids may flow into the housing, and is open at the bottom for discharge of the solids. A shoe 4 has a cylindrical portion 5 which fits in opening 3 and a rectangular portion 6 having an undersurface constituting part of a cylindrical surface. This shoe defines a passage for solids from opening 3 onto the valve rotor 7. Shoe 4 is preferably adjustable vertically, as by bolts 4a, to main substantial contact with rotor 7 as the rotor or the shoe or both these parts wear in use.

The opposite end walls of housing 1 are provided with aligned openings to receive shaft 8 and

with outwardly extending interiorly threaded cylindrical bosses 9 encircling said openings and the shaft 8. Packings 10 engage the shaft 8 within bosses 9 and are pressed against the walls of the housing by glands 11 which are screwed into the bosses and which, preferably, carry bushings 12 to support shaft 8. Sprocket 20 is keyed to one end of shaft 8 outside of the adjacent gland 11. Chain 21 extends around sprocket 20 and around a similar sprocket 22 on the rotor of motor 23. The motor 23 rotates rotor 7 by means of these sprockets and chain.

Valve rotor 7 is keyed to shaft 8 within housing 1 and its outer cylindrical surface is engageable with the lower cylindrical surface of shoe 4. As is shown, this rotor has a plurality of compartments 26 open at the cylindrical surface of the rotor, these compartments being defined by the opposite end walls 27 of the rotor, the hub wall 28, radial walls 29 extending between the end walls 27 and arcuate flanges at the outer ends of the radial walls.

It will be understood that when housing 1 is attached to the lower portion of a hopper solids may flow from the hopper into the compartments of the rotor which are open to the interior of shoe 4 and that when the rotor is turned the solids within any compartment are emptied out as the open side of the compartment is turned downwardly.

A valve rotor reversing lever or arm 30 is rotatably mounted on the outer end of shaft 8. This arm has a portion 31 extending toward motor 23 and lying between the upper and lower throws of chain 21. At its free end portion 31 carries two chain slides 32 pivotally attached thereto as by bolts 33. The chain slides 32 lightly engage the drive chain 31 when it is being driven normally, the upper chain slide lying on the top of the upper throw of the chain and the lower slide lying against the underside of the lower throw of the chain. The other end of arm 30 includes a counterweight 34 and an arm 35 which extends between two limit compression springs 36 and 37, and at its free end is attached to arm 38 of a dash pot 39. Arm 35, by moving vertically around hub 30, engages with its free end spring pressed pins 40 and 41 of microswitches 40a and 41a disposed above and below arm 35, respectively. By thus engaging pins 40 and 41, arm 35 actuates a switch 45 moving it by means of solenoids 46 and 47 to reverse the direction of rotation of the motor 23 and rotor 7.

As shown in Figure 4, the electrical elements in this system include a motor 23 of the conventional three-phase alternating current type, a double-throw, double-pole switch 45, a pair of solenoids 46 and 47 for actuating switch 45 and moving it to the right-hand position illustrated or to the opposite position, and a main switch 48 to connect up the wiring of the circuit to the power source.

It will be appreciated by those skilled in the art, however, that other reversible motor systems than the one herein illustrated may be employed. A direct current motor may, for instance, be employed, in which case the same double-throw, double-pole switch system may be used with the solenoid and microswitches, and the field of the motor may be reversed to effect reversal of the direction of rotation of rotor 7 to accomplish the objects and purposes set forth above.

From the foregoing description it will be understood that so long as the load exerted by motor 23 is less than a predetermined maximum

amount, as when no pieces of solids extend out of a compartment 26 and interfere with rotation of rotor 7, the motor will drive chain 21 with a certain amount of slackness in its upper or pulling throw. During this time upper shoe or slide 32 will rest on the chain and arm 35 will be disposed substantially horizontally with its free end disposed approximately midway between pins 40 and 41. Referring to the wiring diagram shown in Figure 4, it may be assumed that the circuit under these circumstances is as shown with a double-throw, double pole switch 45 in the right-hand position and switches 40a and 41a in the open position. The current is flowing through the circuit with a main switch 48 closed. So long as the rotor operates normally and there is no jamming, the motor will rotate in one direction, and upon jamming the motor will tighten the upper throw of the chain whereby slide 32 will be elevated and arm 35 will move vertically around pivot 30 so that eventually it engages pin 41. Thus, solenoid 47 is actuated, throwing switch 45 to the left-hand position whereby two phases of three phase motor 23 are reversed and the motor reverses the direction of its rotation. If the clinker causing the jam is not thus broken and cleared away so that the motor will continue to rotate with the switch in a left-hand position, the lower throw of the chain will be tightened and lower slide 32 will be moved downwardly and arm 35 moved upwardly, striking pin 40. Solenoid 46 is thereby actuated and switch 45 is moved to the right-hand position as illustrated in the drawing and the rotor is again reversed so that it again rotates in its original direction. In this manner the rotor of the feeder may be repeatedly and rapidly reversed in rotational movement, and this reversing action will continue so long as any overloading of the motor exists.

When solids in the form of pieces of different sizes are being handled, the desire is to rotate the rotor 7 constantly in one direction, which, for purposes of illustration, here may be assumed to be counterclockwise as one views Figure 1. As the rotor is so rotated, solids feed down into the compartments of the rotor. So long as these pieces are small enough to pass into the compartments, the rotor may be rotated by the exertion of a predetermined amount of pull on the drive chain. However, when pieces too large to pass entirely into a compartment of the rotor are encountered, and, for example, one of these pieces is partly within the rotor and partly within the shoe 4, the rotor will rotate until it brings the piece of solid against the left-hand side of the shoe 4 with a sharp impact depending in force on the speed of rotation of the rotor. Thereupon the load of the rotor will increase beyond the predetermined amount due to the stoppage of the rotor, the rotor will be reversed and the piece of solid will be struck against the right-hand side of shoe 4, when the rotor will again reverse. In this way the solid will be repeatedly subjected to hammer and anvil-like blows struck alternately on opposite sides of it until it is broken sufficiently for the rotor to rotate freely.

It will be understood from the foregoing description that this invention provides a rotary feeder for solids of various sized pieces which will reciprocate rapidly when pieces too large to handle are encountered and will continue to strike such pieces alternately on opposite sides until breakage of the pieces occurs. In this manner the feeder automatically clears larger pieces with-

out attention of an operator and with little, if any, delay in the handling of the solids.

Subject matter shown or described but not claimed herein is being claimed in my co-pending application, Ser. No. 4,970, filed January 29, 1948, now Patent Number 2,538,320 of January 19, 1951.

Having thus described the present invention so that others skilled in the art may be able to understand and practice the same, I state that what I desire to secure by Letters Patent is defined in what is claimed.

What is claimed is:

1. A device for feeding solids comprising a rotary valve including a member through which such solids may flow and a rotor engaging said member and having radial compartments open at the periphery of the rotor to receive solids passing through said member and move them beyond said member, means including a reversible motor for rotating said rotor, means including an electric switch for reversing said motor, and motor load-sensing means for actuating the motor reversing means when the load exceeds a predetermined amount, said load-sensing means comprising a pivoted lever engageable with said switch and means actuated when rotation of said valve is impeded for pivoting said lever.

2. A device for feeding solids comprising a rotary valve including a member through which such solids may flow and a rotor engaging said member and having radial compartments open at the periphery of the rotor to receive solids passing through said member and move them beyond said member, means including a reversible motor and a driven chain for rotating said rotor, means including an electric switch for reversing said motor, and motor load-sensing means for actuating the motor reversing means when the load exceeds a predetermined amount, said reversing means including a lever connected to the rotor rotating means for movement to engage said switch when the motor load exceeds said predetermined amount, said load-sensing means comprising a pivoted lever having one arm engageable with said switch, and means operatively associated with said chain and the other end of the lever for pivoting the lever.

3. A device for feeding solids comprising a rotary valve including a member through which such solids may flow and a rotor engaging said member and having radial compartments open at the periphery of the rotor to receive solids passing through said member and move them beyond said member, means for rotating said rotor including a reversible motor, a chain and sprockets operatively connected to the motor and rotor and engaged by said chain, means for reversing said motor including an electric switch, motor load-sensing means for actuating the motor reversing means when the load exceeds a predetermined amount, said load-sensing means comprising a slide riding the chain between the sprockets and movable relative to the sprockets with fluctuations in the tension of the portion of the chain engaging the slide, and a pivoting lever attached to said slide and engageable with said switch to actuate the latter.

4. A device for feeding solids comprising a rotary valve including a member through which such solids may flow and a rotor engaging said member and having radial compartments open at the periphery of the rotor to receive solids passing through said member and move them beyond said member, means for rotating said rotor in-

cluding a reversible motor, a chain and sprockets operatively connected to the motor and rotor and engaged by said chain, means for reversing said motor, and motor load-sensing means for actuating the motor reversing means when the load exceeds a predetermined amount, said reversing means comprising an electric switch operatively connected to the motor and a lever connected to the motor load-sensing means and movable relative to the switch to engage and actuate said switch and reverse the motor, and said load-sensing means comprising a slide connected to the lever and riding the chain between the sprockets to move the lever and thereby actuate the switch as the load on the motor varies and the tension in the chain fluctuates.

5. A device for feeding solids comprising a rotary valve including a member through which such solids may flow and a rotor engaging said member and having radial compartments open at the periphery of the rotor to receive solids passing through said member and move them beyond said member, means for rotating said rotor including a reversible motor, a chain and sprockets operatively connected to the motor and rotor and engaged by said chain, means for reversing said motor, and motor load-sensing means for actuating the motor reversing means when the load exceeds a predetermined amount, said reversing means comprising two electric switches operatively connected to the motor and a lever connected to the load-sensing means and movable to engage and actuate said switches alternately to reverse the motor whenever the motor load exceeds said predetermined amount, and said load-sensing means comprising slides connected to said lever and riding each throw of the chain to move the lever and thereby actuate the switches as the load on the motor fluctuates.

6. Apparatus for handling solids including pieces larger than a predetermined size which comprises a valve rotor having a radial compartment to receive said solids, means for rotating said rotor including a motor, sprockets in the motor, and rotor, and a drive chain extending over said sprockets, spaced apart stationary abutments adjacent to the rotor and engageable by pieces which are larger than said predetermined size and which are in said compartment, and means responsive to an increase in load on said rotor rotating means incident to the impacts of the said large pieces of solids against the abutments for reversing the direction of rotation of the rotor upon each such impact, said reversing means including a reversing switch, a pivoted lever engaging said switch and means actuated by said chain for pivoting said lever.
